United States Patent Office

Des. 233,939
Patented Dec. 17, 1974

233,939

AQUARIUM

Samuel Shalom, 577 Grand St.,
New York, N.Y. 10002

Filed Sept. 28, 1972, Ser. No. 293,049

Term of patent 14 years

Int. Cl. D30—02

U.S. Cl. D30—6

FIG. 1.

FIG. 2.

FIG. 3.

FIG. 4.

FIG. 5.

FIG. 6.

FIG. 7.

FIG. 8.

FIG. 1 is a perspective view of an aquarium showing my new design;

FIG. 2 is a rear elevational view thereof;

FIG. 3 is a bottom plan view thereof;

FIG. 4 is a side elevational view;

FIG. 5 is the perspective view of a modified form of the aquarium, wherein an additional exterior seam is provided centrally along the longitudinal surfaces;

FIG. 6 is a rear elevational view thereof;

FIG. 7 is a bottom plan view thereof; and

FIG. 8 is a side elevational view.

I claim:

The ornamental design for an aquarium, substantially as shown and described.
